UNITED STATES PATENT OFFICE

OCTAIVE J. BROUSSEAU, OF SEATTLE, WASHINGTON, ASSIGNOR TO ALEXINA BROUSSEAU, OF SEATTLE, WASHINGTON

WRENCH

Application filed November 5, 1928. Serial No. 317,224.

This invention relates to wrenches, and has for its object the perfecting of tools of this character to render the same more efficient and convenient to operate than other wrenches hitherto in use.

A further object is to provide a strong and durable wrench comprising few parts of inexpensive construction, arranged to be readily adjusted to accommodate work of different characters and sizes.

More specific objects and advantages of the invention will appear in the following description.

The invention consists in the novel construction adaptation and combination of parts hereinafter described and claimed.

In the accompanying drawing,—

Figure 1 is a side elevation of a wrench embodying my improvements; Fig. 2 is a plan view of the same, a portion of the handle being shown in longitudinal section; and Fig. 3 is a perspective view of the inner jaw member of the wrench.

In said drawing, the reference numeral 5 represents a wrench shank having rigid therewith at one end the stationary jaw 6 disposed, preferably, at right angles with respect to the shank. The other end of the shank extends as a bar 7 which is screw threaded, as at 8, for a nut 9 which serves to secure a tubular handle element 10, sleeved upon the bar 7, in place against the shank shoulder 5¹.

The shank 5 is of an oblong shape in transverse section to provide plane side surfaces 11 with upper and lower edges of circular segmental shape which are provided with screw threads 12 engaging the internal threads of an adjusting nut 13. Adjustably mounted upon said shank is a yoke or frame, shown separately in Fig. 3, the same comprising a body portion having side plate elements 14 extending the entire length of the frame and spaced apart to receive the wrench shank 5 therebetween, said plate elements being joined at one end of the frame to provide a plane surface 15, indicated by dotted lines in Fig. 1, and which is adapted to seat against the under edge 16 of the shank 5.

17 represents the movable jaw which is

formed integral with and depends from the yoke frame below its seating surface 15.

At or about its midlength the frame is provided with a strap element 18 adapted to extend from one side plate 14 to the other as a loop over the shank, the size of the loop and its position relative to the frame surface 15 being such as will permit vertical swinging movements to the frame.

The side plate elements 14 are adapted to extend through openings provided in the adjusting nut at opposite sides of the shank 5, and are arranged to couple said frame to the nut for unitary movement longitudinally of the shank by the provision upon the frame plate 14 of spaced lugs 19 and 20 to bear against the respective ends of the nut, so that when the nut is turned in one rotary direction or the other the engagement of the nut with the screw threads of the shank will cause the movable jaw to be carried toward or from the stationary jaw, as desired.

The opposing ends 21 and 22 of the respective lugs, which shoulder against the ends of the adjusting nut, are curved to permit oscillatory movement to the frame. To enable the nut to be mounted between the companion lugs of the frame's side elements, which extends through the nut, the lugs 20 may be provided by "upsetting" or turning the ends

of the side plates upon themselves; or, as shown, by forming said lugs as blocks 23 and welding or riveting the same to the respective side plates subsequent to inserting the latter through the nut. The lugs 20, moreover, are disposed at a distance from the rear end of the frame to provide thumb pieces at either side of the shank whereby the operator may rock the frame to swing the movable jaw element thereof into or from engageable relation with a pipe or other piece of work which is to be seized between the wrench jaws 6 and 17, in other words actuate the movable jaw into desired adjustment angularly with respect to the fixed jaw.

The wrench is regulated by adjusting the movable jaw 17 longitudinally of the shank by means of the nut 13. During such adjustment or set-up movement of the movable jaw the frame occupies the angular relation, ap-

proximately, to that in which it is represented in Fig. 1 with respect to the shank 5 and its stationary jaw 6.

Such angular relation of the movable jaw—or its idling position, as it may be termed—is accomplished either by swinging by its handle the wrench as a whole in a non-gripping direction or by the workman suitably swinging the movable jaw through the medium of the frame arms.

While I have illustrated and described the invention with respect to a pipe wrench, I do not wish to limit myself thereto, as it may advantageously be used with unserrated jaws for turning polygonal nuts and the like.

What I claim, is,—

1. In a wrench, the combination with a shank having a stationary jaw at one end thereof, said shank having segmental screw threads along its upper and lower edges, of a frame member mounted upon said shank for longitudinal and oscillatory movements, and a nut mounted upon said shank and coupled to said frame member for unitary motion therewith longitudinally of the shank, the internal screw threads of the nut engaging the threads of said shank, said frame member including a movable wrench-jaw rigid with and depending from one end of side bars laterally arranged to said shank, the other end of the frame members being bifurcated to extend through openings provided by the nut at opposite sides of the shank and terminating in elements adapted to be engaged by the thumb of the operator for regulating the oscillatory movement of the frame and the movable jaw with respect to the shank.

2. In a combination with a shank rigid with the fixed jaw of a wrench having an interiorly screw threaded regulating nut mounted for longitudinal movement thereon, of a frame member, said frame member comprising a pair of side bars arranged laterally with respect to said shank and secured in integral relationship, one to the other, by a yoke projecting over said shank and a movable jaw disposed below said shank, said side bars being arranged to project rearwardly of said yoke to extend through the regulating nut and having at opposite ends of said extending portion, lug elements arranged for bearing engagement to the front and rear portions respectively, of said nut, and means provided by one of said lugs whereby said frame member may be oscillated to regulate the angular adjustment of the movable jaw with respect to the fixed jaw of the shank.

60 Signed at Seattle, Washington, this 6th day of October, 1928.

OCTAVER J. BROUSSEAU.
